LEANDER CAREY

BY

Leander L. Carey

his ATTORNEY.

UNITED STATES PATENT OFFICE

104,765

DESIGN FOR A SANDAL

Leander Carey, Medford, Mass., assignor to
Collela & Leighton Shoe Co., Lynn, Mass.

Application December 10, 1936, Serial No. 66,432

Term of patent 3½ years

To all whom it may concern:

Be it known that Leander Carey, a citizen of the United States and resident of Medford, Mass., in the county of Middlesex and State of Massachusetts, has invented a new, original, and ornamental Design for a Sandal, of which the following is a specification, reference being had to the accompanying drawing, forming part thereof, in which

Fig. 1 is a plan view of the sandal showing my new design; and

Fig. 2 is a side view of the sandal shown in Fig. 1.

An important feature of the design relates to

formation of the vamp of two pieces of material arranged symmetrically, each of said pieces having a relatively narrow end secured to the sole at one edge of the forward part of the shoe and spreading in the opposite direction into two branches one of which is attached to the opposite edge of the sole near the tip and the other of which is attached to said opposite edge adjacent to the forward end of the shank.

I claim:

The ornamental design for a sandal, as shown and described.

LEANDER CAREY.
